CLAIM

The ornamental design for a dental implant device, as shown and described.

DESCRIPTION

FIG. 1 is a top, front perspective view of the first embodiment of a dental implant device of our design.

FIG. 2 is a front view thereof.

FIG. 3 is a top plan view thereof.

FIG. 4 is a bottom plan view thereof.

FIG. 5 is a top, front perspective view of the second embodiment of the dental implant device of our design.

FIG. 6 is a front view thereof.

FIG. 7 is a top plan view thereof; and,

FIG. 8 is a bottom plan view thereof.

1 Claim, 8 Drawing Sheets
